ACTUATING MECHANISM

Frederic E. Bertrand, Lynn, Mass., assignor to
United Shoe Machinery Corporation, Paterson,
N. J., a corporation of New Jersey

Application September 7, 1934, Serial No. 743,036

12 Claims. (Cl. 74—518)

This invention relates to mechanism of the character of that through which actuating forces are applied by an operator, as by a treadle, to produce successive steps in the operation of a machine.

An example of a machine to which my invention may be applied is furnished by the sole-rounding apparatus of Letters Patent of the United States No. 882,009, Mayo, March 17, 1908. Here, opposite clamping members are first caused to approach each other for contact with the material to be operated upon and then to apply considerable pressure to retain said material against displacement while the rounding cut is being made. To obtain for this purpose movement through a relatively large distance with a transmission of a small force and to reverse this effect by increasing the force while decreasing the distance traveled, there has been employed mechanism in which is included a lever for movement by the operator of the machine for actuating the clamping means thereof, this lever having a varying fulcrum-point. First, the lever is fulcrumed comparatively close to the point of reception of power to give the desired extent of travel to the transmitting point with little effort on the part of the operator, this being followed by movement about a fulcrum closer to the transmitting point, so the power-ratio is increased. The present invention, utilizing the same principle, has as an object the provision of highly efficient yet simple mechanism by which with a few strong elements the change of fulcrum may be effected with little wear, with complete absence of noise and with positive maintenance in its active position of the fulcrum-point employed during the transmission of the maximum force. In the attainment of this object, I utilize an hydraulic device, combining with an actuating lever, shown herein as a treadle, a plurality of fulcra, one of which is supported by a displaceable fluid, together with means for controlling this fluid. Preferably, this control is made effective in the movement of one of the fulcra. As herein illustrated, the treadle-lever has at one extremity a foot-pad for depression by the operator and at the other extremity power-transmitting connections, there being near the former portion a shiftable member furnishing one fulcrum and near the latter portion a second fulcrum supported by the hydraulic device. Connections from the shiftable member control the hydraulic device to render it active or inactive. The device which I prefer to employ comprises a fluid-containing cylinder and a piston operating therein and provided with a passage governed

by a valve. This valve, in turn, is controlled by some such means as a cam movable under the influence of the shiftable member upon which the treadle-lever turns initially. Closure of the valve locks the previously movable piston, so it offers a rigid support for the lever-fulcrum which it carries.

In the accompanying drawing a particular embodiment of my improved actuating mechanism is shown in side elevation, with portions in section.

A base 10, which may be a portion of the frame of the machine parts which are to be actuated, has pivoted upon it by the pin 12 a bell-crank-lever 14, one arm 16 of which extends in a generally horizontal direction and has threaded through it a stop-screw 18 contacting with the base to limit the clockwise rotation of the lever, as seen in the drawing. An upwardly extending arm 20 of the bell-crank carries a roll 22 upon which rests a generally horizontal surface 24 at the under side of a treadle-lever 26. A torsion-spring 28 surrounding the pin 12 acts to hold the roll 22 normally against the depressing effect of the treadle-lever with the screw 18 determining the angle at which the arm 20 of the bell-crank lies and, consequently, the downward force necessary to displace it. This shiftable support for the treadle-lever is adjacent to the extremity to which the operator is to apply power. This may be through a foot-pad 30 depending from said lever. To permit some travel of the operator's foot after the actuating movement has been completed, the pad 30 is pivotally connected to the lever 26 at 32 and is arranged to yield against the expansive force of a spring 34.

At the opposite extremity of the treadle from the foot-pad is joined a rod 36 by which power is to be transmitted. In proximity to this connection is a fulcrum-pin 38 for the treadle. It extends horizontally between spaced lugs 40, 40 upon a cap 42 carried by a piston 44 movable vertically in a cylinder 46 which may be formed in the base 10. The cap and piston-body may, if desired, be formed integrally. At the lower end of the piston is a passage 48 surrounded by a seat which may receive contact of a valve 50 to close the passage. The vertical stem 52 of the valve is guided in a sleeve 54 depending from an upper piston-head 56. This head is recessed, and in this recess is a spring 58 interposed between the head-wall and a collar 60 fast upon the stem to exert a constant seating force upon the valve. To hold said valve normally open, there is arranged to turn about the pin 38 a cam 62 toward which

the valve-stem 52 is urged by the spring 58. An arm 64 projects upwardly from the cam and is connected by a rod or link 66 to a sleeve 68 trunnioned upon the upper extremity of an arm 70 fast 5 to the pivot-pin 12 of the bell-crank-lever 14. The rod, at opposite sides of the sleeve 68, is threaded and carries nuts 72, by the adjustment of which the effective length of the rod and the normal relation of the cam 62 to the valve-stem 10 may be altered.

Normally, the treadle-lever 26, initially fulcrumed upon the roll 22 in its elevated position, is held with the foot-pad 30 raised by an unillustrated spring associated with the machine to 15 which the actuating mechanism is applied. The cam 62 holds the valve 50 open, so free flow through the passage 48 of such a liquid as oil, which the cylinder 46 contains, allows the piston 44 and the pivot-pin 38 of the treadle which it 20 supports to rise unrestrained. When the operator, by pressure of his foot upon the pad 30, depresses the treadle, it turns the lever 26 upon the roll 22 to elevate the rod 36, to the pivot-pin 38 and its support carried by the piston being 25 lifted without material resistance. Since the lever-arm from the fulcrum-roll 22 to the rod 36 is long, as compared with that from said roll to the foot-pad, a comparatively short foot-movement rapidly lifts the rod through a much greater 30 distance, and this may be assumed to move a clamping member into engagement with a work-piece. It is at this period in the operating cycle that the elements are shown in the drawing. There is such a resistance offered to the further 35 travel of the rod 36 that the lever 14 yields against the force of its spring 28, the roll 22 passing outwardly and downwardly along the surface 24 of the descending treadle-lever 26. Through the rod 66 and its connected arms the cam 62 is rotated anti-clockwise, removing it from above the valve-stem 52. The spring 58 is thus allowed to lift 40 the valve 50, which closes the passage 48 in the piston. There is now locked in the cylinder beneath the piston a body of a substantially non-compressible liquid, the piston-cap 42 thus becoming an immovable support for the pivot-pin 38. About this fulcrum the movement of the treadle continues, the downward yield of the roll 22 taking place without effect. Now, the transmitting arm of the treadle is short as compared 45 to that to which power is applied through the pad 30, and this increase of leverage creates through the rod 36 a greater pressure upon the work. Upon release of the pad by the operator, the treadle mechanism is restored to its initial 50 relation, the bell-crank-lever 14 turning clockwise until the stop-screw 18 engages the base, the cam 62 opening the valve 50 so the piston is again free to move in the cylinder, displacing the oil 55 through the passage 48. The pressure upon the machine elements is relieved and they are returned to normal, the treadle mechanism being ready for another operation.

Having described my invention, what I claim 60 as new and desire to secure by Letters Patent of the United States is:

1. An actuating mechanism comprising a lever, a plurality of fulcra therefor, a support for one of the fulcra, said support including a displaceable fluid, and means for controlling the displacement of the fluid.
2. An actuating mechanism comprising a lever, a plurality of fulcra therefor, a support for one of the fulcra, said support including a displaceable fluid, and means made effective by move-

ment of one of the fulcra for controlling the displacement of the fluid.

3. Treadle mechanism comprising a lever having a foot-pad and power-transmitting connections near its opposite extremities, an hydraulic device upon which the lever is fulcrumed adjacent to its power-transmitting end, and controlling means for the hydraulic device actuated upon depression of the foot-pad. 5

4. Treadle mechanism comprising a lever having a foot-pad and power-transmitting connections near its opposite extremities, an hydraulic device upon which the lever is fulcrumed adjacent to its power-transmitting end, a shiftable member furnishing a fulcrum adjacent to the foot-pad end, and connections to the shiftable member for controlling the hydraulic device. 10

5. Treadle mechanism comprising a lever having a foot-pad and power-transmitting connections near its opposite extremities, an hydraulic device upon which the lever is fulcrumed adjacent to its power-transmitting end, a shiftable member furnishing a fulcrum adjacent to the foot-pad end, connections to the shiftable member for controlling the hydraulic device, and 15 means arranged to vary the normal position of the shiftable member. 20

6. Actuating mechanism comprising a cylinder and a piston operating therein, one of these elements being fixed against movement and the other being movable, there being a passage between the opposite sides of the piston, means for controlling flow through the passage, a lever fulcrumed upon the movable element, a fulcrum member for the lever movable by said lever, and 30 connections to said fulcrum member for operating the flow-controlling means. 35

7. Actuating mechanism comprising a cylinder and a piston operating therein, one of these elements being fixed against movement and the other being movable, there being a passage between the opposite sides of the piston, a valve controlling the flow through the passage, a lever fulcrumed upon the movable element, a member turning about such fulcrum of the lever to 40 control the valve, a fulcrum member for the lever movable by said lever, and connections to said fulcrum member for turning the controlling member. 50

8. Actuating mechanism comprising a cylinder and a piston operating therein, one of these elements being fixed against movement and the other being movable, there being a passage between the opposite sides of the piston, a valve controlling flow through the passage, means for closing the valve, a lever fulcrumed upon the movable element, and means movable by the lever for opening the valve. 55

9. The combination with a base, of a cylinder carried thereby, a piston movable in the cylinder and having a passage between its opposite sides, a valve movable upon the piston to control the passage, a treadle fulcrumed upon the piston, a lever pivoted upon the base and furnishing a 60 fulcrum for the treadle, and connections to the lever for operating the valve.

10. The combination with a base, of a cylinder carried thereby, a piston movable in the cylinder and having a passage between its opposite sides, a valve movable upon the piston to control the 65 passage, a treadle fulcrumed upon the piston, a lever pivoted upon the base and furnishing a fulcrum for the treadle, a spring acting upon the lever, an adjustable stop limiting the movement 70

75

of the lever by the spring, and connections to the lever for operating the valve.

11. The combination with a base, of a cylinder carried thereby, a piston movable in the cylinder and having a passage between its opposite sides, and having a valve movable upon the piston to control the passage, a spring for closing the valve, a cam movable upon the piston for opening the valve, a treadle fulcrumed upon the piston, a lever pivoted upon the base and furnishing a fulcrum for the treadle, and a link joining the lever to the cam.

12. The combination with a base, of a cylinder

carried thereby, a piston movable in the cylinder and having a passage between its opposite sides, a valve movable upon the piston to control the passage, a spring for closing the valve, a cam movable upon the piston for opening the valve, a treadle fulcrumed upon the piston, a lever pivoted upon the base and furnishing a fulcrum for the treadle, a link joining the lever to the cam, and means arranged to vary the effective length of the link.
